SEWING MACHINE

George Sauer, Berwyn, Ill., assignor to Union
Special Machine Company, Chicago, Ill., a cor-
poration of Illinois

Application August 22, 1940, Serial No. 353,647

3 Claims. (Cl. 112—221)

This invention relates to sewing machines, and is especially concerned with means whereby the timing, i. e., the operative relation between the feed and the stitch-forming instrumentalities may be adjusted. More specifically the invention has reference to lock stitch sewing machines of a fully-enclosed, self-lubricating type such as disclosed in a copending patent application Serial No. 312,898 filed by me jointly with Albert M. Schweda on January 8, 1940, wherein the needle bar is actuated from an upper or main shaft enclosed within the needle arm; wherein the rotary hook and the feed are actuated from a parallel rotary shaft which extends into the base of the machine and which is driven from the upper shaft through a train of spur gears housed within the standard; and wherein the oil used for lubrication is taken from a supply within the machine base which is closed at the bottom, with interposition of a sealing gasket, by a removable cover plate.

Having regard to lock stitch sewing machines the usual practice of mechanics and adjusters is to delay the active stroke of the feed as much as possible so that the maximum time interval is afforded for manipulation of the needle thread loop by the rotary hook. However, a setting which will be suitable for sewing relatively thin materials, may be unsatisfactory for heavier materials when excessive delay in the active or work-advancing movement of the feed will be attended by entry of the needle into the material before the active feed stroke is completed. It thus becomes necessary to frequently change the feed timing to adapt the machines for operation upon different materials.

For the purpose of changing the timing in lock stitch sewing machines of the specific type hereinbefore referred to, it has been the custom of the adjusters to rotatively shift the drive gear wheel on the lower shaft. This procedure consumes considerable time in its accomplishment since it entails the removal of the fluid sealed bottom cover plate of the machine base, and, when frequently done, is liable to result in leakage around the bottom seal as well as contamination of the oil supply.

My invention has for its chief aim to overcome the above drawbacks, which objective is realized as hereinafter more fully set forth, through provision of a simple adjustment means which is so disposed within the frame of the sewing machine as to be readily accessible without necessitating the removal of the oil-sealed bottom cover of the machine base.

Other objects and advantages will appear from the following detailed description of the attached drawings, wherein

Fig. 1 is a view partly in front elevation and partly in longitudinal section, of a sewing machine conveniently embodying my invention.

Fig. 2 is a view partly in elevation and partly in section taken as indicated by the angled arrows II—II in Fig. 1.

Fig. 3 is a fragmentary view in horizontal section taken as indicated by the angled arrows III—III in Fig. 2.

Fig. 4 is a fragmentary view showing the elevation of the lefthand end of the machine, with the front cover of the needle head removed to expose the parts at the interior; and

Fig. 5 is a perspective view of the means whereby the timing of the machine may be adjusted.

The construction of the illustrated sewing machine is substantially like that disclosed in the copending application to which reference has already been made in that its frame has a hollow base 1 whereof the top 2 serves as a work support, and a communicating hollow standard 3 which sustains a hollow arm 4 above the work, said arm terminating in a hollow needle head 5. As shown, the end of the head 5 is closed by a cover 6 held in place by several screws 7, see Figs. 1 and 2. Confined to endwise reciprocation in guide bushings 8 and 9 in the top and bottom of the head 5 is a bar 10 in the lower protruding end of which a needle 11 is secured. Cooperating with the needle 11 in stitch formation in a well known manner below a throat plate 12 recessed into an extension of the top of the work support 2 immediately beneath the head 5, is a rotary hook 13 of appropriate design. By means of set screws 14, the rotary hook 13 is adjustably secured to the protruding end of a shaft 15 which extends into the base 1, and which, through a pair of gears shown at 16 in Fig. 3 is rotated from a horizontal shaft 17 suitably journaled within said base.

The feeding mechanism of the machine includes a feed dog 18, the teeth of which operate upwardly through slots 19 in the throat plate 12, said dog being supported by a carrier bar 20 whereof the rear end (Figs. 2 and 3) is pivotally connected at 21 to a rocker 22. As shown, the rocker 22 is oscillated from an eccentric 23 on the shaft 17, through a link composed of telescoping parts 25 and 26 whereby horizontal to and from movements are communicated to the feed dog 18. The component 25 of the link has a pivotal connection at 27 with a "lazy" bar 28 which is suspended from the end of an arm

29 on a regulating shaft 30 also journalled within the machine base 1. By rotative adjustment of the shaft 30 in a well known manner, the horizontal or feeding stroke of the feed dog 18 can be increased or decreased, or reversed. Extending downward from the feed bar 20 is an arcuate arm 31, which, through a drop link 32, is connected to a small crank 33 at the lefthand or outer end of the shaft 17, whereby the necessary up and down or lift movements are imparted to the feed dog 18. As shown in Figs. 2 and 3, the feed bar 18 extends through an opening 35 in the front side wall 36 of an offset portion 37 of the base 1, a fluid tight seal being formed by flexible washers 38 on said bar which are pressed against the inner face of said wall at the region of said opening, by a leaf spring 39. Reactive upon the feed dog 18 incident to feeding is a presser foot 40 at the lower end of a presser bar 41 which extends upward into the needle head 5 and which is subject to the downward pressure of a spring 42 within said head, see Figs. 2 and 4. By this means partly shown in Fig. 4 and comprehensively designated by the numeral 43, the presser foot 40 may be lifted as required from time to time during the sewing.

The drive mechanism of the machine includes a horizontal upper shaft 45 from which the feeding and stitch-forming instrumentalities derive their movements either directly or indirectly as will presently be seen. As shown, the shaft 45 is journalled within the arm 4 and protrudes through a bearing 46 at the righthand end of the machine frame where it carries a combined hand and belt wheel 47. Through a train of spur gears 48, 49 and 50 within the standard 3, rotation is communicated from the upper shaft 45 at unison speed and in the same direction to the lower shaft 17. From Fig. 1 it will be noted that the upper shaft 45 extends through a bearing 51 a cross partition 52 within the arm 4 into the head 5; and mounted on the end of said shaft within the head is a rotary actuator or crank member 53 from which the needle bar 10 is reciprocated endwise through a pitman 55.

In practice, a supply of oil is maintained in the base 1 of the machine at the level conventionally indicated in Figs. 1 and 2 for the automatic lubrication of the moving parts in the manner described in the aforementioned copending application, said base being closed at the bottom by a removable screw-secured cover plate 56 with interposition of a compressible gasket 57 to form a fluid tight seal. The purpose of this construction is to enable access to the interior of the base in the event that part replacements should become necessary.

Heretofore changes in the timing of the feed relative to the movement of the needle in a sewing machine such as has been described were accomplished by rotatively shifting the drive pinion 59 on the lower shaft 17, which, as has been already explained elsewhere herein, entailed the removal of the cover plate 56 and breaking of the seal 57. This undesirable and time consuming procedure is avoided in accordance with my invention as a consequence of the following construction:

As shown in Figs. 1, 4 and 5, the rotary actuator 53 consists of two components which are respectively designated by the reference characters 60 and 61. The component 60 is in the form of a sector shaped enlargement and may be either integrally constructed with the upper or needle shaft 45 at the distal end of the latter, or welded

thereto, said plate having an arcuate slot 62 in concentric relation to the shaft axis. The component 61 is mounted on the needle shaft 45 immediately behind the component 60 with capacity for rotative shifting thereon and is weighted as at 63 to counterbalance the needle bar 10 and the pitman 55. The shank of a headed clamp screw 65 passes through the slot 62 in the component 60 and threadedly engages into the component 61 to normally secure said components in fixed relation. As shown, a set screw 66 is provided for securing the component 61 against accidental displacement on the shaft 45 after its adjustment. The eccentric or crank pin 67 to which the upper end of the pitman 55 is connected is carried at the end of a short arm 68 whereof the fulcrum stem or shank 69 is rotatively adjustable in the crank component 61 and fixable in adjusted position by a pair of set screws 70 and 71. The pivot stud 72 (Fig. 1) whereto the lower end of the pitman 55 is coupled with the needle bar 10, engages a vertical guide way 73 within the needle head to restrain said bar against rotation. The needle thread take-up of the machine, indicated at 75 in Figs. 4 and 5 is connected to the stud 69 and its movements modified by virtue of being pivotally connected at 76 to an arm 77 which rocks on a fixed axis 78 within the needle head 5.

From the described construction it will be seen that for changing the timing of the machine, instead of taking off the bottom cover plate 56 of the base, it is merely necessary to remove the two upper screws 7 which secure the needle head cover 6 and to swing said cover aside on the third screw when access can be immediately had from the exterior to the clamp screw 65 of the rotary actuator 53. Upon loosening the clamp screw 65, the component 61 is shifted about the upper shaft 45 relative to the component 60 until the desired new operative relation between the movements of the feed dog 18 and the needle 11 is attained. Then, if necessary, the rotary hook 13 may be re-timed by shifting it circumferentially about its shaft 15 upon loosening of the set screws 14. Finally, with the screws 65 and 14 re-tightened, the head cover 6 is replaced and secured. The timing adjustment is thus easily and quickly accomplished without loss or possible contamination of the oil supply within the base.

Having thus described my invention, I claim:

1. In a sewing machine, a feeding element; a drive shaft; means deriving motion from the shaft for actuating the feeding element; a needle; mechanism for actuating the needle including a two-part crank member whereof one component is rigid with and forms one end terminus of the shaft and has a flat surface of relatively large area transverse to the shaft, and whereof the other component is counterweighted and rotatively adjustable on the shaft, carries the crank center and has a flat transverse surface of relatively large area in frictional contact with the flat surface of the rigid component; and clamp means for releasably securing said adjustable component to said rigid component, and a pitman connecting the crank member with the needle.

2. In a sewing machine, a frame which has a base, a standard rising therefrom and an overhanging arm supported by the standard and terminating in a hollow needle head with a removable end cover; a feeding element; a needle and a carrier bar therefor confined to endwise move-

ment in the needle head; a drive shaft journaled on the arm and extending into the needle head; means deriving motion from the shaft for actuating the feeding element; and mechanism for actuating the needle including a two-part crank member whereof one component is rigid with and forms the terminus of the shaft within the head and has a flat surface of relatively large area transverse to the shaft, and whereof the other component is counterweighted and rotatively adjustable on the shaft, carries the crank center and has a flat transverse surface of relatively large area in frictional contact with the flat surface of the rigid component, clamp means accessible from the exterior upon retraction of the needle head cover for releasably securing said adjustable component to said rigid component, and a pitman connecting the crank member with the needle bar.

3. In a sewing machine, a needle; a comple- 20
